US0D1049522S

(12) **United States Design Patent** (10) Patent No.: **US D1,049,522 S**
(45) Date of Patent: ** Oct. 29, 2024

(54) **CLEANING MACHINE**

(71) Applicant: **NETALUX, naamloze vennootschap**, Beringen (BE)

(72) Inventors: **Emmanuel Flaam**, Diest (BE); **Pieter Cretskens**, Diest (BE); **Thijs Peeters**, Diest (BE)

(**) Term: **15 Years**

(21) Appl. No.: **35/518,363**

(22) Filed: **Jul. 5, 2023**

(80) **Hague Agreement Data**

Int. Filing Date: **Jul. 5, 2023**

Int. Reg. No.: **DM/231288**

Int. Reg. Date: **Jul. 5, 2023**

Int. Reg. Pub. Date: **Sep. 15, 2023**

(51) **LOC (14) Cl. 15-05**

(52) **U.S. Cl.**

USPC **D32/15**

(58) **Field of Classification Search**

USPC D32/1, 15-16, 21; D15/14, 144, 199; D23/202, 213, 223-225

CLAIM

The ornamental design for a cleaning machine as shown and described.

DESCRIPTION

1.1 : Front left top perspective view

1.2 : Back right top perspective view

1.3 : Front

1.4 : Back

1.5 : Left

1.6 : Right

1.7 : Top

1.8 : Bottom

1.9 : Back right top perspective view with open cover

1.10 : Front left top perspective view with open cover

1.11 : Top view with open cover

1.12 : Front left top perspective view

1.13 : Back right top perspective view

1.14 : Front

1.15 : Back

1.16 : Left

1.17 : Right

1.18 : Top

The broken lines showing in **1.1-1.18** are for the purpose of illustrating portions of the cleaning machine that form no part of the claimed design; the reference views **1.1-1.11** show the cleaning machine in state of use with a tube and laser head attached, the tube and laser head are disclaimed; views **1.12-1.18** show the cleaning machine without the tube and laser head.

1 Claim, 18 Drawing Sheets
